United States Patent Office.

CHARLES KLEIN, OF ALBANY, NEW YORK.

Letters Patent No. 74,917, dated February 25, 1868.

IMPROVED FOLDING CRADLE.

The Schedule referred to in these Letters Patent and making part of the same.

TO ALL WHOM IT MAY CONCERN:

Be it known that I, CHARLES KLEIN, of Albany, in the county of Albany, and in the State of New York, have invented certain new and useful Improvements in Cradles; and do hereby declare that the following is a full, clear, and exact description thereof, reference being had to the accompanying drawings, and the letters of reference marked thereon. In the annexed drawings, making a part of this specification—

Figure 1 represents my cradle adjusted and ready for use, and

Figure 2 represents the same folded up in a convenient form, and ready for storing away.

AA, in the annexed drawings, represent suitable rockers for a cradle, of any desired material, and BB represent the sides, constructed with suitable legs, and in any desired style, size, and manner, hinged to the rockers AA, so as to allow both sides to fold one way on the said rockers and on each other. One of the sides, B, has a suitable bottom, C, composed of a series of parallel horizontal slats, held together by means of cross-bars or slats hinged to it, so as to fold upward against said side. The other side is provided with a slat or shoulder, for the side of the bottom, C, opposite the hinges, which secures it to the side B, to rest on when adjusted for use. Ends or end-pieces, DD, are hinged to one of the sides, so as to fold inward and rest on said side, and are provided with catches or hooks, xx, which catch on pins or in loops or staples on the other side, to hold the whole frame together when required for use. It will be seen that by raising up or folding the bottom, C, and detaching the catches xx, the ends DD may be folded inwardly, and then the sides BB may be laid over on each other, and on the rockers AA. The cradle or crib is then in a convenient and compact form for moving about, or packing out of the way under a table, or bed, or any place desired.

Having thus fully described my invention, what I claim as new, and desire to secure by Letters Patent, is—

The sections BB, bottom C, rockers AA, and end-pieces DD, when the several parts are hinged together, as specified, for the purposes set forth.

In testimony that I claim the foregoing, I have hereunto set my hand, this 26th day of December, 1867.

CHARLES KLEIN.
